UNITED STATES PATENT OFFICE

HERMAN H. RUBIN, OF NEW YORK, N. Y.

GRIP STRAP

Application filed July 3, 1931. Serial No. 548,496.

The present invention relates to an improvement in grip straps. One of the objects thereof has been to provide a grip strap, toggle, or assist grip capable of being produced in attractive designs and incorporating a variety of materials with a maximum of strength and durability.

One embodiment of my invention is illustrated in the drawing accompanying the present specification and in which

Figure 1 is a side elevation with portions broken away and portions partly in longitudinal section to disclose interior parts;

Figure 2, a fragmentary view of a portion 15 of a grip as shown in Figure 1;

Figure 3, a transverse section on the line 3—3 of Figure 2;

Figure 4, a front elevation, with portions broken away, of a slightly modified form of 20 grip strap;

Figure 5, a transverse section on the line 5—5 of Figure 4;

Figure 6, a fragmentary longitudinal section of the upper end of a modification; and 25

Figure 7, a similar view of the upper end of a further modified form of grip strap.

Referring to the drawing, Figure 1 represents a grip strap employing a multiple stem provided at one end with an attaching device whereby the grip strap is secured to an interior wall of a vehicle, and at the opposite end with a pompon secured thereto by suitable anchoring means concealed by a hand hold or by a mold or ferrule. The multiple 30 stem above referred to comprises a core 1 of resilient material, such as rubberized fabric of suitable cross sectional shape and area, in the form of device shown in Figure 1, the core 1 is enclosed by a cover 12 of tubular fabric secured by any suitable means, as stitching 2, glue, or both, as will be well understood. To form the stem, as shown in Figure 1, a strip of resilient core material 35 suitably covered, has its ends bent toward each other to form a loop 3 at one end of the stem. The ends of the covered strip forming the opposite end of the stem are secured together by means of a suitable clamp as a ring 4. A pompon 5 is attached to one end 40 of the stem by means of a bail 6 interengag-

ing with said ring 4, said bail and said ring being preferably of stiff galvanized wire or other suitable material.

The pompon fastening just described is concealed by suitable means, shown in Figure 1 as a hand hold 7, and in Figure 4 as a mold or ferrule 8. A band 9 of fabric, metal, or other suitable material, is secured around the parallel portions of the multiple stem adjacent to its upper or looped end in such a manner as to provide a closed loop which passes through a ring 10 of a bracket 11.

In Figure 4 I have illustrated a form of grip strap in which the resilient core is enclosed by a braided tubular covering 13, as distinguished from the strip of fabric indicated at 12 in Figures 1 and 2.

The hand hold 7, applied to a stem such as the multiple stem above described, or its equivalent, serves the combined function of 70 concealing the pompon attachment, of providing an effective hand gripping element, and of stiffening a portion of the necessary length of stem, thus amplifying, in effect, the resiliency of the remainder of the stem; 75 so that a grip strap embodying these features of construction, even without the provision of springs or the like, will have the necessary resiliency to remain in extended position and to readily return to extended position after 80 being distorted in use. The hand hold 7 may be made of wood, metal or other suitable rigid or semirigid substance, with any desired kind of ornamental or other suitable covering material applied to the exterior. The illustrated hand hold is covered by a tubular braiding 14.

In the modification illustrated in Figure 6 the multiple stem comprises two separate 90 pieces of resilient core material arranged in a single continuous tubular covering 13, which is bent between the ends of said separate pieces of core material to form an upper or exposed end of the multiple stem, the opposite end being completed in a manner similar 95 to that illustrated in connection with the device shown in Figure 1. In the modification figure, the ring 10 is anchored to the upper end of the stem by a bolt 15 passing through 100 both layers of the stem and secured in place,

as by means of an ornamental nut 16, said ring 10 being assembled with a bracket 17 for supporting the grip strap in operative position in a vehicle or the like. In this form of

5 my improved device, it is unnecessary to provide a loop with which to engage the ring of the attaching mechanism; and the bent portion of the continuous tubular fabric conceals the upper ends of the enclosed resilient cores, thus making it unnecessary to perform any finishing or concealing operation in the form of thread windings, crocheted coverings or the like at this point.

Figure 7 illustrates a further modification 10 of my invention in which separate pieces or strips of suitably covered core material are assembled in parallel relation and are held together at their upper ends by means of a clamp comprising a rivet 18, which engages a 15 yoke 19 cooperating with the ring 10 of an attaching bracket 11 to support the grip strap in a vehicle or the like. In this form of the device, it will be desirable to conceal the yoke 19, as well as the ends of the rivet 18 by suitable means such as a crocheted cover 20 which is secured, as by stitches 21, to the fabric cover 13 of the cores 1.

The constructions hereinabove described 20 provide an effective grip strap more particularly adapted for use in automobile fitting or furnishing. They are capable of being embodied in pleasing designs and in desirable and dependable embodiments combining, therefore, pleasing appearance with great 25 durability. Moreover, these devices lend themselves to mechanical production which permits them to be made and sold at relatively small cost, as compared with devices for a similar purpose upon, or in connection with 30 which substantial amounts of hand work are required. The resilient core is preferably non-stretchable and affords a sturdiness and resilience ample for the requirements of a device of this type and in which the capacity 35 to retain pleasing appearance is of substantial importance.

I claim:

1. In a grip strap, the combination of a 40 resilient member having its ends bent toward each other to form a double stem with a loop at one end and means at the other end for holding together said ends of the resilient member, an attaching device engaging the looped end of the stem, and a gripping device 45 secured at the opposite end of the stem.

2. In a grip strap, the combination of a 50 fabric covered resilient member having its ends bent toward each other to form a double stem with a loop at one end, a pompon secured 55 at the opposite end of said stem, and an attaching device engaging said loop.

3. In a grip strap, the combination of a 60 stem comprising parallel portions of resilient material, an attaching device at one end of 65 said stem, a pompon at the other end thereof

and a clamp for securing said pompon to the stem and for retaining the ends of said portions of resilient material in assembled relation.

4. In a grip strap, the combination of a 70 stem comprising a plurality of separate resilient core members arranged in parallel relation, a tubular fabric cover enclosing said members, and means for clamping ends of the covered cores together, a pompon secured to 75 one end of said stem, and an attaching device at the other end.

5. In a grip strap, the combination of a 80 stem comprising a plurality of separate resilient core members arranged in parallel relation, and a tubular fabric cover enclosing 85 each of said members, anchoring means at the end of the stem for securing an attaching device thereto, a clamp at the opposite end, and means at each end for concealing said anchoring device and said clamp respectively.

6. In a grip strap, the combination of a 90 multiple stem comprising a single flexible tubular core cover, separate resilient core members arranged therein, said cover being 95 bent upon itself between said core members, and the covered core members being arranged in parallel relation, anchoring means at one end of the stem for securing an attaching device thereto, and a clamp at the other end of 95 the stem for holding end portions of said core members in assembled relation.

In testimony whereof, I have signed my name to this specification this 30th day of June, 1931.

HERMAN H. RUBIN.
